UNITED STATES PATENT OFFICE.

MICHAEL JANKIEVICH, OF ELMHURST, NEW YORK.

GROUND-LEVELING MACHINE.

1,380,106.

Specification of Letters Patent. Patented May 31, 1921.

Application filed August 13, 1920. Serial No. 403,389.

To all whom it may concern:

Be it known that I, MICHAEL JANKIEVICH, a citizen of Lithuania, residing at Elmhurst, county of Queens, and State of New York, have invented certain new and useful Improvements in Ground-Leveling Machines, of which the following is a specification.

This invention relates to improvements in ground leveling machines, particularly to machines for preparing and leveling the ground of tennis courts, play grounds, baseball parks, drive-ways, and the like.

It is the principal object of the invention to provide a machine which levels the ground by collecting stones and other obstructions, provides a layer of sand, clay or gravel and by the operation of rakes and brushes evenly distributes the sand or gravel.

20 A further object of the invention is the provision of a machine of this character in which one or the other of the leveling means may be conveniently cut out of operation while for instance the prepared ground is 25 firmly rolled out by rollers, and which can be easily steered during all these operations by the operator.

With the above and other objects in view, this invention resides in the novel features 30 of construction, arrangement of parts and combination of elements to be hereinafter more fully described, claimed and illustrated in the accompanying drawings in which—

Figure 1 is a top plan view of the machine 35 constructed according to the present invention.

Fig. 2 is a side view of the same in section along the line 2—2 of Fig. 1.

Fig. 3 is a top plan view of the steering 40 roller and its coöperating parts, partly in section on line 3—3 of Fig. 2.

Fig. 4 is a top plan view of the crank shaft at the front end of the machine and the brush or rake holder in section along line 45 4—4 of Fig. 2.

Fig. 5 is a detail view of a brush.

Fig. 6 is an end view in section along line 6—6 of Fig. 2.

Fig. 7 is a detail view of the stone rake.

50 Fig. 8 is a detail view of the front brush.

Fig. 9 is a detail view of one of the rake teeth and

Fig. 10 is a side view of the machine.

In the machine frame 10 a motor 11 is 55 mounted provided with a starting handle 12 and clutch throwing lever 13. Near its

lower rear end the frame carries a platform 14 for the operator and in front of the same steering wheel 15 for the operation of the steering roller 16 on the axle 17 suspended 60 by hangers 18, 19 and 20 of which 19 is suspended from a bar 21 Fig. 3 secured in the side walls 21' and 22 of the frame through the center of which a steering shaft 23 is extending, the lower end of which is 65 secured to the roller 16 and which passes through a turn-table 24 coöperating with a similar turn-table 25 suspended from the platform 26, carrying the motor, by means of rods 27 and 28. 70

In front of the motor the platform 26 carries a pair of links 29 in which a shaft 30 is journaled carrying a sprocket wheel 31 on one, and a similar wheel 32 Fig. 1 at the opposite side of the machine. In approximately its middle the shaft 30 carries a fixed clutch member 33 and a movable clutch member 34 coöperating with the member 33 Fig. 1 over which a belt 35 is running, guided over the motor shaft and adapted to 75 be operated by the belt shifting lever 13.

Over the sprocket wheel 31 a chain 36 is guided which is also guided over a sprocket wheel 37 upon the axle 38 of a roller 39 journaled in the machine frame. On the axle 38 85 is also mounted in front of the sprocket wheel 37 another sprocket wheel 40 over which a chain 41 is guided which runs over a sprocket wheel 42 on a shaft 43 journaled in the machine frame 10 which shaft carries 90 within a hopper 44 at the front end of the machine frame a stirring device 45 for the sand or clay 46 with which the hopper is filled for a purpose hereafter more fully to be described. 95

The hopper 44 has in its rear wall a door or opening 47 adapted to be closed by the slide 48 sliding in guides 49 and 50 secured to the outer wall of the hopper. This slide has at its outer face the shape of a rack 51 100 with the teeth 52 of which the teeth 53 of a star wheel 54 are in mesh arranged upon a shaft 55 in the machine frame on which also a bevel gear 56 is arranged in mesh with a similar bevel gear 57 on a shaft 58 extending 105 through the rear wall of the machine where it is provided with a hand operating wheel 59 by means of which the slide 48 may be operated to close the opening of the hopper in a desired manner as will be obvious.

To the hanger 19 a holder 60 is secured 110 for a brush 61 working against the outer

periphery of the roller 16, while a similar holder 62 is secured to the machine frame and carries a brush 63 working against the periphery of the roller 39 to keep the same 5 clean.

On a shaft 64, journaled in the machine frame, a sprocket wheel 65 is secured over which a chain 66 is guided, running over a sprocket wheel 67 on a crank shaft 68 journaled in the frame near the bottom thereof. The shaft 64 is rotated by means of a belt 69 guided over a pulley 70 on said shaft laterally disposed to the sprocket wheel 65 which is also guided over a pulley 71 by the 15 side of the sprocket wheel 31 on the shaft 30.

The crank shaft 68 is connected by links 72 and 73 with a movable plate 74 carrying rake teeth 75, or if desired, with a plate 76 carrying a brush 77 as indicated in Fig. 5. 20 These plates are exchangeably held within a frame 78 secured in the sides of the machine frame and provided with upstanding links 79 to the upper ends of which the front end of an operating lever or rod 80 one on each 25 side of the machine is pivotally secured at 80' which is extended to the rear of the machine and through the rear wall thereof where it is provided with a toothed segment 81. Intermediate its length the rod 80 is 30 provided with noses upon which are pivoted pivotal link connections 82 and 83 as shown in Fig. 2.

The front wall of the hopper is extended as at 84 in order to guide the same in front 35 of the roller 39, while in front of this extension 84 a holder 85 is secured to link connection 82 and this holder carries a stone rake 86 suspended on the opposite side of the machine frame in a similar manner as 40 indicated at 87 Fig. 7. In front of said rake 86 a shaft 88 is journaled in the machine frame and carries a sprocket wheel 89 over which a chain 90 is guided which also runs over a sprocket wheel on the shaft 64. On 45 the shaft 88 a pulley 91 is secured laterally disposed to the sprocket wheel 89 over which a conveyer 92 is running which is also guided over a pulley 93 of a stone collector 94 secured at the front end of the machine 50 frame which is provided with a front door 95 at its lower front end through which the stone may be removed. To the link 83 is pivotally secured a holder 83' which is rotatably secured to one end of a shaft 95, journaled with its other end in the opposite side wall of the machine, which shaft or axle 95 carries a wire brush 96. A chain 81''' is connecting the wheels 81''' at the rear wall 55 of the machine.

60 Near the sprocket wheel 31 on one end of the shaft 30 is secured a fixed clutch member 101 adapted to be engaged by a movable clutch member 102 on shaft 30 which is adapted to be operated by means of an operating handle 103 at the rear of the machine 65

platform 26. By means of this clutch the rake operating shafts and gears are connected to the driving shaft and when it is desired to dispense with their services during the operating of the other elements, for 70 instance the brush elements, the clutch member 101, 102 are separated by the suitable operation of the handle 103.

In a similar manner the sprocket wheel 32 on shaft 30 near the opposite end thereof 75 has laterally disposed thereto a fixed clutch member 104 adapted to be engaged by a movable clutch member 105 also on shaft 30 upon the operation of the clutch actuating handle 106 also at the rear end of the machine platform 26. These clutch members 104, 105 when connected, will connect the operating gears and shafts of the brush elements with the driving shaft. 80

As shown in Fig. 3, the steering handle 15 85 is moved above a segment plate 107 at the rear end wall of the machine provided with teeth 108 at its upper face between which the handle 15 is temporarily engaged according to the direction of driving the machine. 90

In operation, the operator starts the motor after the hopper 44 has been filled with sand or clay, according to the nature of the work to be performed by the machine, and connects the driving shaft by means of the 95 clutch with the motor shaft, and by the operation of the clutch handles 103, and 106, either simultaneously or alternately, couples the driving shaft with the brush-or rake-operating means as required, while the stone 100 rake will rake the stones etc., encountered upon the conveyer which will transport the same into the stone-collecting vessel from where they may be removed, if required or necessary. The opening in the hopper bottom is regulated according to the quantity 105 of sand or clay to be distributed over the ground by means of the hand-wheel 59. According to requirement, either a plate 74 provided with rake teeth 75, or a plate 76 provided with a brush 77 may be placed into the 110 frame 78.

It will be clear that according to the nature of the work to be performed, the succession of the single operations is to be 115 charged as for instance first the rakes may be used to level the ground, or the operation of the rakes may be dispensed with and the ground be worked by the brushes and rollers only for instance after a rain both of the 120 rollers may be used for leveling purposes.

Having thus described my invention what I claim as new and desire to secure by Letters Patent of the United States is—

1. A ground leveling machine of the character described, comprising in combination with a motor carrying frame, a steering-roller in said frame, a ground leveling roller in front of said steering-roller, means for supplying sand, and clay to the ground in 125 130

- front of said leveling roller, a stone rake, a collector, and means for carrying the stones collected by said rake to said collector, brushes for cleaning said rollers during 5 their rotation, rakes and brushes for equally distributing the sand, and clay and means for operating said parts simultaneously and alternately from said motor.
2. In a ground leveling machine of the 10 character described, the combination of a motor carrying frame with a steering roller in the rear part of the frame, a foot board for the operator on the rear end wall of the machine, means for operating said steering 15 roller, a ground leveling roller in front of said steering roller, an operating shaft in said frame, clutches for connecting and disconnecting said operating shaft with and from said motor, a sand and clay hopper 20 having a bottom opening, and manually operated means for closing said opening partly and wholly, means for collecting stones, means for raking and brushing the sand and clay dispensed from said hopper, and the 25 ground in front of said leveling roller, and means for connecting said parts to the operating shaft.
3. In a ground leveling machine of the 30 character described, the combination of a motor carrying frame, with a steering and a ground leveling roller carried in said frame, an operating shaft, means for connecting and disconnecting said shaft, to and from said motor, a sand and clay hopper 35 having a bottom opening, an agitating roller in said hopper, and means for connecting said agitating roller with the ground leveling roller, a slide provided with rack-teeth at its outer face for closing the bottom opening of said hopper, a star wheel, two bevel gears, and a manually operated rod for operating said slide, an operating shaft and means for connecting said shaft to the motor and disconnecting it therefrom 40 for operating the parts.
4. In a ground leveling machine of the 45 character described, the combination of a motor carrying frame, with a steering and a ground leveling roller in said frame, means for supplying sand and clay to the ground in front of said leveling roller, an operating shaft, a crank shaft near the lower front end of the machine, means for coupling said operating shaft to the motor 50 and to said crank shaft, a carrier frame in the front of said crank shaft, adapted to receive a plate carrying a rake, exchangeably secured in said carrier frame, and links connecting said crank shaft and said rake 55 plate within said carrier frame, brushes for equally distributing the sand and clay, and means for operating said parts simultaneously and alternately from said motor, substantially as described and for the purpose 60 set forth.
5. In a ground leveling machine of the character described, the combination of a motor carrying frame with a steering and a ground leveling roller in said frame, means for supplying sand and clay to the ground 65 in front of said leveling roller, an operating shaft, and a crank-shaft, means for connecting said operating shaft to said motor and to said crank shaft, a carrier frame in front of said crank shaft, an exchangeable plate in 70 said carrier frame carrying a rake or brush for equally distributing the sand and clay, and links connecting said carrier plate to said crank shaft, an upstanding link on said carrier frame, a rod pivotally secured to the upper end of said link and extended through the rear end wall of the machine, an operating handle on said rod, a hopper above said rod, a rack bar connecting said hopper and said bar, and a bar parallel to said rod adapted 75 to engage the teeth of said rack and extended through the rear end wall of the machine, a handle on said bar pivotally secured to the outer end of said rod, and means for operating said parts simultaneously and alternately from said motor, substantially as 80 described and for the purpose set forth.
6. In a ground leveling machine of the character described the combination of a motor carrying frame with an operating 85 shaft, a ground leveling roller in said frame, means for supplying sand and clay to the ground in front of said leveling roller, rakes and brushes for equally distributing the sand and clay, a fixed and a movable clutch member in approximately the 90 middle of said shaft, means for operatively connecting said rakes and brushes to said operating shaft, clutch members at the ends of said shaft for engaging and disengaging 95 said rakes and brushes with and from said shaft, means for operating said parts simultaneously and alternately from said motor, and means for shifting said clutches near 100 the rear end of the machine.
7. In a ground leveling machine of the character described, the combination of a motor carrying platform and frame therefor, with a steering and a ground leveling roller in said frame, two cooperating turntables for said steering roller, a steering handle, and a toothed segment over which said steering handle is operated, brushes for 105 cleaning said rollers, an operating shaft, means for coupling and uncoupling said shaft to and from the motor, a sprocket wheel on said shaft, a sprocket wheel on the axle of the ground leveling roller, and a chain connecting both sprocket wheels, a 110 hopper adapted to receive sand and clay, a stirrer in said hopper adapted to be operated from the axle of said ground leveling roller, an extension of one of the side walls of said hopper for delivering the sand in front of said ground leveling roller, means 115 120 125 130

for adjustably opening and closing the hopper bottom, means for collecting stones, a collecting vessel at the front of the machine, means for transferring the collected stones into said receptacle, a brush and rake frame in rear of said receptacle, an operating rod for the same, links secured to said operating rod, a wire brush connected to one of said links, means for coupling and

uncoupling the operating means for said rakes and brushes to and from said operating shaft, and operating handles near the rear end of said machine for coupling and uncoupling and for operating said slide and said rake and brush. 10 15

In testimony whereof I have affixed my signature.

MICHAEL JANKIEVICH.
